UNITED STATES PATENT OFFICE.

THURMAN ADDISON DINSMORE, OF CAMERON, WEST VIRGINIA.

PERMUTATION-PADLOCK.

SPECIFICATION forming part of Letters Patent No. 733,820, dated July 14, 1903.

Application filed May 12, 1903. Serial No. 156,765. (No model.)

To all whom it may concern:

Be it known that I, THURMAN ADDISON DINSMORE, of Cameron, in the county of Marshall and State of West Virginia, have invented 5 a new and useful Improvement in Permutation-Padlocks, of which the following is a specification.

My invention relates to improvements in locks, being particularly applicable to padlocks, its object being to provide a lock which can be opened without a key.

My invention consists in certain novel features of construction, arrangement, and combination of parts, as will be hereinafter fully 15 described, and pointed out in the claims, reference being had to the accompanying drawings, in which—

Figure 1 is a side view of my improved lock. Fig. 2 is vertical section of the same in its 20 locked position. Fig. 3 is a similar view in its unlocked position. Fig. 4 is a detail perspective view. Fig. 5 is a vertical transverse section taken on line 5 5, Fig. 2.

In the present embodiment of my invention 25 as herein shown applied to a padlock the casing is composed of the front and rear faces A and A', secured to each other by the bolts a, openings a' being left near each upper corner to receive the front and rear ends of the hasp 30 B. Said hasp is pivoted within the casing at its rear end, and said rear end is provided with a heel or extension B'. Just above and to the rear of the pivot the hasp is hollowed out, as at b', said hollowed-out portion being 35 adapted to rest upon the top edge of the side of the casing when the lock is open. The front end of the hasp is provided with a hook B², which is adapted to be caught and held by the spring-latch C, pivoted at its lower end 40 within the casing and having the spring c pressing against it to normally throw it forwardly on its pivot. A finger-piece C' projects from the latch through a slot a³ in the front face of the lock-case. The front face 45 of the lock is also provided with the central circular aperture a², within which is fitted the dial D. Said dial is somewhat larger than the central aperture a², but is provided with a hub extension d, which fits snugly within 50 the aforesaid central aperture, but not so tightly as to bind. Said dial is provided with a central bore, within which fits the axle of

the rear tumbler of the lock. Extending rearwardly from the hub extension d is a reduced collar d', the periphery of which is polygonal 55 to fit into the central aperture in the front tumbler of the lock. The axle E of the rear tumbler F is circular in cross-section for a greater portion of its length, but is squared at its outer end, upon which squared portion is 60 fitted and held by a screw the pointer H. The rear end of axle is reduced and journaled in the rear face of the lock-case. At a short distance from its rear end axle E is squared, as at e, and immediately in front of this squared 65 portion is a circular flange e', which separates the two tumblers F and G, the tumbler G being fitted on the collar d', and the tumbler F being provided with a central aperture, which corresponds in shape to the squared portion e of 70 the axle and on which it fits.

The tumbler F is provided with a radial slot f, the corners of which are rounded, as shown, the corner f' being rounded more than the opposite corner. The tumbler G is 75 provided with a similar radial slot g, the corner g' of which is rounded more than the opposite corner. The respective parts are placed in the proper positions, as shown in Fig. 1, the pointer H being held on by a 80 screw h. The thickness of the heel or extension B' is at least equal to the distance from the front face of tumbler G to the rear face of tumbler F, so that it will be necessary to bring the radial slots in both tumblers into 85 registry with each other before the heel B' can be swung inwardly to allow the hasp to be unlocked.

The dial D is provided with a circular scale of numbers or other characters, and the 90 tumbler G is fitted on the collar d', so that the slot g bears the desired relation to the zero-point of the scale, and the tumbler F is fitted on the pointer-axle E in its desired relation to the point of H and the parts of the 95 case secured together. At the upper central portion of the front face of the casing is an indicating-line I. Now to open the lock, the parts being about as shown in Fig. 1, it being noticed that the tumblers can be rotated 100 without striking the heel of the hasp, the zero-point on the dial D is brought into alignment with the indicating-line I and then turned to the right the required number of

- spaces, (the number being known only to the operator.) This movement brings the radial slot *g* adjacent to the heel of the hasp. The pointer *H* is now fixed at the indicating-line 5 I and then turned to the left a number of spaces, (known only to the operator,) whereupon the latch *C* is pushed to the side, releasing the hooked front end of the hasp. The hasp can now be opened, as the heel or 10 rear end extension will swing into the registering radial slots *f* and *g*. The hasp when thrown as far back as it will go rotates the tumblers together forwardly a slight distance. Now when the front or hooked end 15 of the hasp is swung downwardly again the tumblers are carried backwardly until the heel *b* leaves the radial slots and permits the tumblers to be rotated freely and destroy the registry of the radial slots.
- 20 Any desired combination may be set, and it can be changed as frequently as desired by changing the tumblers on their axes with relation to the scale on the dial and the point of the pointer.
- 25 It will be seen that I provide a simple, cheap, and efficient padlock which can be opened without the use of a key, thus doing away with the annoyance of having to provide several persons with a key and the consequent 30 liability of loss of the keys. It will also be noticed that the hasp cannot be opened until the hooked end thereof is released by moving the spring-latch *C* to one side after the slots in the tumblers have been brought into registry.
- 35 Having thus described my invention, what I claim as new, and desire to secure by Letters Patent, is—
1. In a permutation-lock, the combination 40 with a casing, a plurality of rotating tumblers mounted therein and provided with radial slots in their periphery, a hasp pivoted near one end within said casing having a rear extension or heel, and provided with a hook-shaped front end, a manually-operated latch 45 mounted in said casing and adapted to engage and lock the hook-shaped front end of the hasp and means for rotating the tumblers relatively, whereby the radial slots will be brought into registry to permit the rear extension or heel of the hasp to be swung into 50 said registering slots subsequent to the releasing of the hooked front end of the hasp by the spring-latch.
2. In a permutation-padlock, the combination 55 with a casing a dial rotatably fitted in the front face thereof and having a rear extension, a tumbler mounted on said extension and provided with a radial slot in its periphery, a pointer-shaft extending through said 60 dial and journaled at its rear end in the casing having a portion of its periphery polygonal, a tumbler having a central aperture mounted on said polygonal portion and provided with a radial slot in its periphery, a 65 hasp pivoted near one end within the casing, a rear extension or heel projecting from the pivoted end thereof and having a hook-shaped front end, a manually-retracted spring-latch mounted within the casing and adapted to engage and lock the front end of the hasp, the tumblers being relatively rotated to bring the radial slots into registry with each other adjacent to the rear extension or heel of the hasp whereby said heel may be swung into 70 said registering slots subsequent to the release of the hook-shaped front end of the hasp and permit opening the hasp.

THURMAN ADDISON DINSMORE.
